(57) **CLAIM**

We claim the ornamental design for a chair, as shown and described.

DESCRIPTION

FIG. 1 is a perspective view of a chair.

FIG. 2 is a side view of the chair of FIG. 1.

FIG. 3 is a front view of the chair of FIG. 1.

FIG. 4 is a rear view of the chair of FIG. 1.

FIG. 5 is a top view of the chair of FIG. 1.

FIG. 6 is a perspective view of another chair.

FIG. 7 is a side view of the chair of FIG. 6.

FIG. 8 is a front view of the chair of FIG. 6.

(Continued)

FIG. 9 is a rear view of the chair of FIG. 6.
FIG. 10 is a top view of the chair of FIG. 6.
FIG. 11 is a perspective view of another chair.
FIG. 12 is a side view of the chair of FIG. 11.
FIG. 13 is a front view of the chair of FIG. 11.
FIG. 14 is a rear view of the chair of FIG. 11.
FIG. 15 is a top view of the chair of FIG. 11.
FIG. 16 is a perspective view of another chair.
FIG. 17 is a side view of the chair of FIG. 16.
FIG. 18 is a front view of the chair of FIG. 16.
FIG. 19 is a rear view of the chair of FIG. 16.
FIG. 20 is a top view of the chair of FIG. 16.
FIG. 21 is a perspective view of another chair.
FIG. 22 is a side view of the chair of FIG. 21.
FIG. 23 is a front view of the chair of FIG. 21.
FIG. 24 is a rear view of the chair of FIG. 21.
FIG. 25 is a top view of the chair of FIG. 21.
FIG. 26 is a perspective view of another chair.

FIG. 27 is a side view of the chair of FIG. 26.
FIG. 28 is a front view of the chair of FIG. 26.
FIG. 29 is a rear view of the chair of FIG. 26.
FIG. 30 is a top view of the chair of FIG. 26.
FIG. 31 is a perspective view of another chair.
FIG. 32 is a side view of the chair of FIG. 31.
FIG. 33 is a front view of the chair of FIG. 31.
FIG. 34 is a rear view of the chair of FIG. 31.
FIG. 35 is a top view of the chair of FIG. 31.
FIG. 36 is a perspective view of another chair.
FIG. 37 is a side view of the chair of FIG. 36.
FIG. 38 is a front view of the chair of FIG. 36.
FIG. 39 is a rear view of the chair of FIG. 36; and,
FIG. 40 is a top view of the chair of FIG. 36.
The broken lines shown in the drawings illustrate portions of the chair that form no part of the claimed design.
